ABRADING APPARATUS

Walter L. Keefer, Hagerstown, Md., assignor to
 Pangborn Corporation, Hagerstown, Md., a corporation of Maryland

Application February 6, 1935, Serial No. 5,270

20 Claims.

(Cl. 51—9)

The present invention relates to abrading apparatus, and it is more particularly concerned with apparatus for centrifugally propelling or projecting abrasives.

In its preferred embodiments, my improved abrading apparatus takes the form of a rotating mechanism which is operable to propel or discharge abrasive from a limited peripheral region of the mechanism, and which may be employed to replace air-blast abrasive propelling apparatus in abrading mechanisms. Although apparatus of this general character is in use and represents a substantial advance in the art over the early centrifugal blasting apparatus in which the abrasive is discharged throughout three hundred and fifteen degrees of the wheel or other rotatable mechanisms, such prior apparatus is subject to rapid wear.

The most commonly used of such prior apparatus is provided with a bladed wheel having an abrasive feed conduit with a restricted abrasive outlet and agitator in its center, while other forms feed the abrasive into the paddles from one side in a manner to control the direction of abrasive discharge. However, the abrasive discharge from such prior centrifugal wheels has not been positively restricted to a limited region with the result that stray abrasive is discharged in sufficient quantities to rapidly abrade the wheel housing, reducing the efficiency of the wheel, and increasing the costs of maintenance and operation. It has also been found that the blades of both the wheels and agitators of such prior apparatus wear out rapidly which not only entails considerable expense for new blades, but also involves a loss of valuable time, as the machine must be practically dismantled every time the blades are replaced.

My apparatus overcomes all of the defects of such prior apparatus, is constructed in an entirely different manner, and operates in accordance with basically different principles from the prior apparatus, and which will become apparent from the following objects.

It is a major object of my invention to provide a centrifugal device for propelling abrasives which is of simple construction and which will have a materially longer useful life than apparatus of this character heretofore proposed.

It is another important object of my invention to provide an apparatus for mechanically propelling abrasives which is so designed that the abrasives pass through the apparatus to the discharge area at low velocity, thereby reducing abrasion of the parts to a minimum.

It is another major object of my invention to devise a mechanical abrasive-propelling apparatus having a rotatable mechanism which is operable to discharge abrasive from a predetermined limited peripheral region thereof, and to positively prohibit abrasive discharge from any other region.

My invention further aims to provide a mechanical abrasive-propelling apparatus having a rotatable head which will automatically close during a part of each operating cycle and maintain abrasives in the head, and which will automatically open up and discharge abrasives from the head during another part of each cycle of operation.

A further object of this invention is to provide an abrading apparatus having a rotatable mechanism which will impart substantially solely tangential velocities to abrasives supplied thereto.

Another object of my invention is to provide a mechanical abrasive-propelling apparatus having the parts by which the abrasives are propelled, constructed of rubber, whereby destructive abrasion thereof in operation is reduced to a minimum.

My invention further aims to provide a mechanical abrasive-propelling apparatus which may be quickly and easily disassembled and the parts which are subjected to abrasion during operation, readily replaced in a minimum of time.

A further object of this invention is to provide a centrifugally operable abrasive-propelling apparatus having a rotatable head from which the abrasive is discharged in a stream of predetermined angular width, and which is selectively operable to vary the width of the stream.

It is a still further object of my invention to provide a mechanical abrasive projecting apparatus having a rotatable head, all portions of which will open up once every revolution when they pass a predetermined point and allow the abrasive to be discharged therefrom.

My invention further aims to provide a mechanical abrasive propelling apparatus which utilizes centrifugal force for preventing improper abrasive escape therefrom.

It is another object of this invention to provide a mechanical apparatus for propelling abrasives having a sealing element for preventing improper abrasive discharge from the apparatus, and which automatically adjusts itself to compensate for wear of the sealing element.

Further objects of my invention will become apparent as the specification proceeds in con-

nexion with the accompanying drawings, and from the appended claims. In the drawings:

Figure 1 is a top plan view of the preferred form of my invention.

5 Figure 2 is an elevational end view of the machine illustrated in Figure 1 as it appears when viewed from the right hand end of that figure.

10 Figure 3 is an enlarged longitudinal sectional view of the machine illustrated in Figures 1 and 2, and is taken substantially on the line 3—3 of Figure 2, looking in the direction of the arrows.

Figure 3A is a fragmental sectional view taken substantially on the line 3A—3A of Figure 3.

15 Figure 4 is a view similar to Figure 3, but is taken along the line 4—4 of Figure 2, looking in the direction of the arrows.

Figure 5 is a fragmental perspective view of the driving runner of the apparatus illustrated in Figure 1 and shows the ring and ring groove.

20 Figure 6 is an enlarged fragmental sectional view of runners and the ring and ring grooves of the apparatus illustrated in Figure 1 and shows the action of the rings as they undergo movement from open to closed position.

25 Figure 7 is a fragmental sectional view of a modified form of my invention and illustrates a modified ring and groove assembly incorporated in the apparatus shown in Figure 1.

Figure 8 illustrates another form of abrading 30 apparatus, also forming part of my invention.

Figure 9 is a fragmental elevational view of the rubber rings employed in the device shown in Figure 8 and illustrates them as they appear when removed from the machine.

35 Figure 10 is a fragmental sectional view of another form of abrading apparatus, also forming part of my invention.

Figure 11 is a view similar to Figure 10 but illustrates a further modified form of my invention.

40 Figure 12 is an elevational view of a modified form of sealing ring assembly and which may be used in the apparatus illustrated in Figures 8, 9, 10 and 11, and.

45 Figure 13 is a fragmental sectional view similar to Figure 4, but illustrates a pneumatically operated mechanism, also forming part of my invention, for replacing the spring assembly of that figure.

50 With continued reference to the drawings, wherein like reference characters have been used to designate like parts throughout the several views thereof, and with particular reference to Figures 1 to 6, my abrading apparatus or blasting machine generally consists of a base A, upon which a driving runner B and a driven runner C are rotatably supported. A resilient sealing ring assembly D is disposed between the driving and driven runners and functions to prevent the abrasive from leaving the chamber defined by the runners except at one discharge point. Abrasive is introduced into the device, either by gravity or by pneumatic means, by way of a funnel E. The driving and driven runners 55 are urged towards each other, so as to clamp rings D between them, by means of a spring assembly designated as F.

Supported upon base A, in any suitable manner, are bearing assemblies 10 and 11 which may 70 assume any desired form. In the present instance each bearing assembly preferably consists of a ball bearing 12 and a pair of sealing assemblies 13, which retain lubricant in the bearings and also prevent abrasive contained in the atmosphere 75 from getting at the bearings. Journaled in bear-

ings 10 and 11 is a shaft 14. Power may be applied to shaft 14 in any suitable manner, but in the present instance I have illustrated a pulley 15, with which a belt drive may be associated.

The upper portion of my apparatus is preferably enclosed by a housing 16, which assumes a substantially semi-cylindrical configuration and is preferably equipped with inspection doors 17. Doors 17 are secured to housing 16 in any suitable manner as for instance by means of links 18 and thumb screws 19. Cover 16 is pivotally secured to base A, and to this end it is provided with a handle 20 and a pair of ears 21. Ears 21 are aligned with a pair of similar ears 22 formed on a plate secured to base A and are pivotally connected thereto by means of a pin 23. Pin 23 is secured against displacement with respect to cover 16 by means of a pair of set screws 24 threaded into ears 21. The free end of housing or cover 16 is secured down to base A by means of a stud 26 pivoted to base A, and a nut 27 engaging the upper sides of a pair of ears 28 provided on cover 16. Nut 27 may be removed and cover 16 swung upwardly about pin 23 as an axis to give access to the interior of the machine for a purpose that will presently appear.

The driving runner or rotor will now be described. Secured to a shouldered extremity 31 of shaft 14, by any suitable means such as a key 32, is a driving runner 33, which preferably assumes a disk-like configuration. Secured to driving runner 33, by means of a plurality of circularly spaced machine screws 34 are two distributor plates 35 and 36. Distributor plates 35 and 36 are utilized to smoothly distribute the abrasive 35 throughout 360° of the runner and are also employed to bring the abrasive, which enters the machine in a non-rotative condition, progressively up to the rotative speed of the runner periphery in gradual stages. Plates 35 and 36 are provided 40 with a plurality of annular flanges or projections 38 and 39 respectively which cooperate with each other to define a tortuous or corrugated passage 41, which extends from a region near the axis of the machine outwardly towards the periphery. Plates 35 and 36 have fins 40 and 40a for accelerating the abrasive. Circular lips or flanges 38 and 39 have their faces which are disposed toward the axis of the mechanism inclined at an angle which is less than the angle of repose of 45 the abrasive, with the result that a stationary layer of abrasive builds up upon the inner face of each lip. As the lips further away from the axis of the mechanism possess a greater peripheral speed, and are of greater circular area than 50 those closer to the axis, it is apparent that the abrasive must not only be accelerated as it passes outwardly over the distributor plates, but it must also be smoothly distributed, or spread out over the lips. As a stationary layer of abrasive 55 is always located on the lips during operation of the machine it is apparent that they are protected from excessive wear. Although I have illustrated, and prefer to secure both distributor plates to the driving runner, it is apparent that 60 one or both of the distributor plates may be carried by the driven runner if desired without departing from the spirit of my invention.

Distributor plate 35 is supported within an annular face 42 formed on driving runner 33 70 and terminates short of the periphery thereof. Boss 43 is cut away to define a sealing-ring receiving groove denoted generally as 44.

With reference to Figure 3 of the drawings, it is apparent that the outer periphery of distrib- 75

utor plate 35 defines one wall of groove 44, so that the runner is not subjected to the action of the abrasive. Groove 44 is provided with a curved portion 45, a substantially flat rear wall 5 46, a curved portion 47 and a portion 48 which is substantially straight in section. Curved portion 47 and straight portion 48 are joined by a substantially straight portion 49, which functions as an inclined plane in a manner that will be presently described.

10 Straight portion 49 of groove 44 is provided with a plurality of circumferentially extending grooves or recesses 51 into which extraneous or stray abrasive is adapted to be deposited. Communicating with the bottom of each groove 51 at spaced intervals about the periphery of runner 33 are a plurality of drain holes 52. Abrasive finding its way into grooves 51 is adapted to drain into holes 52 and be centrifugally discharged from the rotor head in a manner to be presently set forth. Also communicating with each groove 44 at spaced intervals about the periphery of the runner 33 are a plurality of apertures 53 which are employed to relieve any air 20 pressure conditions developed in the groove in a manner to be presently set forth. Distributor plate 36, adjacent its periphery, (Figure 3A) is also provided with a plurality of spaced teeth 53' which insure that abrasive leaving the latter 25 will possess a rotative speed as great as that of the distributor plate assembly.

30 Disposed substantially loosely in groove 44 is a ring 54, which is adapted to cooperate with a similar ring carried by the driven runner and control the discharge of abrasive from the apparatus. Ring 54 may be constructed of any suitable material that has the flexibility and the sealing properties required of it in practice, for instance, rubber covered fibre or metallic rope, or a steel wire or a metallic reinforced fabric 40 or rubber material may be used. In the present instance, however, it is preferably constructed of a comparatively soft grade of rubber without reinforcing means of any character. The operation of ring 54 will be set forth in detail hereinafter. The driven runner will now be described.

45 A driven runner 57 is mounted for rotation in a bearing assembly to be hereinafter described and its axis is disposed at a predetermined angle 50 58 with respect to the axis of the driving runner. The driven runner is provided with a smooth cylindrical portion 59 which cooperates with a groove 60 formed in the inner edge of distributor plate 36. A plurality of radially extending passages 60' communicate with groove 60 and function to convey any abrasive finding its way between portion 59 of the driven runner and plate 36, to the innermost groove of the latter. The driven runner is provided with a comparatively 55 long hub 61, whose internal surface is preferably smoothly finished and assumes the shape of a gradually flared cone 62. The small portion of the driven runner hub is provided with a removable member 63, which has a surface conforming to surface 62 and which may be removed after it has become worn in service. If desired the entire inner surface of the driven runner may be made in the form of a removable wear plate, but it has been found that as the 60 stationary abrasive initially contacts the driven runner in the region of member 63, the greatest abrasion occurs in this region, and a wear plate is accordingly only necessary at this point.

70 The outer periphery of the driven runner is

provided with an enlarged portion or boss 65 in which is formed a groove 66. This groove 66 is substantially identically similar to groove 44 described in connection with the driving runner, and therefore similar reference characters, having the subscript *a*, have been applied to the corresponding parts, and they will not be again described. A rubber ring 67 is disposed in groove 66 and cooperates with ring 54 in a manner to be presently set forth.

10 Clamped between a shoulder 69 formed on an enlarged portion of the driven runner, and a nut 71 threaded on the small end of the driven runner, are a pair of bearings 72 and 73, a spacer member 74 and a third bearing 75. Although the bearings may assume any desired form, ball bearings are preferably employed and in this connection it is observed that bearings 72 and 75 both cooperate to resist axial movement of the driven runner to the right (Figure 20 3) and that bearing 73 absorbs thrusts in the other direction. The thrust capacity preponderates in one direction for the purpose of absorbing the centrifugal action of rings 54 and 67. As this type of ball bearing is capable of sustaining an axial load that is substantially as great as its radial load-carrying ability, it is seen that the driven runner is adequately supported for both radial and axial loads.

30 Bearings 72 and 73 are mounted in an axially slidable sleeve 77 and bearing 75 is supported in a spacer sleeve 78 having an oil baffle 79 formed thereon. The left hand end of sleeve 77 is provided with an inwardly directed flange 81, which serves to prevent the lubricant from being 35 centrifugally thrown from the bearings. A ring 82 encircles sleeve 77 and the bearings and spacer 78 are clamped against axial movement in sleeve 77 against ring 82 by means of an end plate 83, which is in turn secured to sleeve 77 by means 40 of cap screws 84 or the like. Mounted in a bore in the end of end plate 83 is a packing assembly 85 which cooperates with the outer surface of the driven runner hub and is secured in place by means of a nut 86 threaded into the end plate. 45

The driven runner is accordingly mounted for rotation in sleeve member 77 and the latter is mounted for axial movement so as to move the driven runner toward and away from the driving runner by means of a support 88, which is secured to cover 16 by means of cap screws 89 or the like. A plurality of shims 91 are preferably disposed between support 88 and cover 16 for a purpose that will be pointed out hereinafter.

50 In order to prevent abrasive from finding its way between support 88 and the end of sleeve 77, a flexible shield 95 is secured to the respective members by means of wires 96 and 97, which force the ends of shield 95 into grooves located in these members. Abrasive is prevented from 55 finding its way into the bearings by a cylindrical shield 98 which is secured to the driven runner by means of cap screws 99. Base A fits shield 98 rather closely, but in order to prevent any abrasive that may get between the parts from working into the bearings, a drain hole 101 is provided in the base member through which the abrasive may gravitate out of the machine.

60 A sealing member 102 tightly engages the bottom portion of support 88 at 103 and is secured to the upper portion of support 88 by means of 70 cap screws 104. Member 102 sealingly cooperates with the outer surface of member 98, and in order to prevent abrasive from working between these two members the outer surface of 75

member 98 is provided with a screw thread 105, which is given the proper pitch to cause abrasive which finds its way between the parts to move to the left and outwardly of the members.

5 Sealing members 98 and 85 accordingly cooperate with hub 61 of the driven runner and support 88 so as to define a fluid tight lubricant chamber, with the result that the bearings may be packed with lubricant when they are assembled and therefore lubricated throughout the life of the machine. If desired however, a grease fitting may be associated with the parts so that additional lubrication may be periodically supplied.

15 Abrasive may be introduced into the interior of the driven head in any suitable manner, but I preferably employ a hopper or funnel member 106, to which a plate 107 (Figure 2) is secured. Plate 107 is secured to the rear face of cover 20 plate 83 by means of two of the screws 84 thereof. Abrasive may be introduced into funnel 106 in any suitable manner, but I preferably allow it to drop by gravity therein from a suitable metering valve which supplies it at a predetermined 25 rate. If desired however, it may be pneumatically carried into funnel 106 or be otherwise introduced without departing from the spirit of my invention. Moreover funnel or spout 106 may be given a suitable configuration, or suitable 30 pneumatic means may be employed to cause the abrasive to spiral in the direction of rotation of the driving and driven runners as it enters hub portion 61 of the driven runner, in order to reduce the velocity difference of the 35 abrasive and the runner at the instant of initial pick-up, and thereby reduce the abrasion that occurs at this point.

The driven runner is preferably urged toward the driving member, and although any means 40 may be employed for this purpose, I preferably make use of a device which is located exteriorly of the mechanism, so that it may be readily adjusted, and it takes the form of a resilient tensioning mechanism. This mechanism will now 45 be described.

With particular reference to Figure 4, an apertured lug 109 is preferably integrally formed on end plate 83 and a threaded member 111, which will be hereinafter termed a screw, extends loosely therethrough. Screw 111 is threaded into a cup member 112, which is preferably constructed of bronze and has a closed bottom for the purpose of preventing abrasive from being introduced between the threads of members 111 and 50 112. Cup member 112 is in turn threaded into a boss or enlarged portion 113 provided on support 88, and is adapted to be locked therein by any suitable means such as a latch 114 and a cap screw 115. A ratchet member 116 is snugly fitted 55 on screw 111 and is preferably locked thereto by means of a pin 117. Ratchet member 116 is equipped with an indicating line 118, which will be termed a hair line. Line 118 cooperates with a similar hair line 119 provided on a latch member 121. Member 121 is pivoted on a pin 122 located in a pair of ears 123 formed on lug 109. Latch 121 is adapted to be selectively engaged in 60 any one of a plurality of notches 124 located in ratchet member 116 for locking screw 111 against 65 70 movement in its various adjusted positions.

Bearing against the rear face of lug 109 is a cup 126. Screw 111 extends through cup 126 and is encircled by a compression spring 127 which acts against the bottom of the cup and reacts 75 against a washer 128 and a nut 129 threaded on

screw 111. The end of screw 111 is provided with a square portion 131, in order that it may be engaged with a wrench and turned so as to adjust the parts in a manner that will be presently set forth.

From the structure just described it is apparent that spring 127, acting through cup 126, lug 109, and end plate 83, urges sleeve 77 to the left, to thereby urge the driven runner toward the driving runner and thereby urge ring 67 into engagement with ring 54. It is also apparent that the force with which the driven runner is urged toward the driving runner may be adjustably varied, either by lifting latch 121 and rotating screw 111 or by tightening nut 129, both of which 15 serve to increase the pressure of spring 127. The force with which the driving and driven runners are urged together directly controls the mode of 20 operation of the machine and I have provided two independent means for increasing or decreasing this pressure in order to simplify the adjustment of the machine, as will presently appear.

Although I have illustrated a resilient means located exteriorly of the machine for urging the 25 driving and driven runners toward each other, and I prefer to use this organization for the reason that it may be readily adjusted while the machine is in operation, it is to be understood that if desired, spring 127 and the associated 30 parts may be omitted or be supplemented by a plurality of springs directly associated with the driving and driven runners without departing from the spirit of the present invention. For instance, axially extending studs may be secured 35 to the driving runner and extend through apertures in the driven runner, and compression springs may be associated with the studs so as to bear against the rear face of the driven runner and nuts threaded on the studs, so as to thereby 40 urge the parts toward each other, and the appended claims are intended to embrace my device when it assumes this form. It is also to be understood that although I have illustrated and prefer to employ a driving and driven runner assembly wherein the driving connection is 45 provided therebetween by virtue of frictional engagement of the rings carried by the respective members, a direct mechanical connection may be provided between the driving and driven runners, without departing from the spirit 50 of my invention. Moreover, power may be applied to both runners if desired.

The operation of my device so far described 55 will now be set forth.

The apparatus as it is shown in Figure 3 illustrates the parts as they appear when operating at their normal running speed, and under these conditions hair line 119 of latch 121 aligns or registers with hair line 118 of ratchet member 116. When the machine is stopped a different condition exists, and before describing the relation of the parts of the tensioning device, it will be assumed that the machine is stopped and that boss 109 is held in engagement with ratchet 60 member 116 under the influence of spring 127. 65

With reference to Figure 3, it is observed that by reason of the angle 58 between the axes of the driving and driven runners, the tops of the runners are disposed closer together than the bottoms thereof. This causes the chamber defined by the runners to be closed at the top and open at the bottom. For the sake of brevity, these sides will be respectively termed the closed and open sides.

As the machine is started from rest and attains normal running speed, which in the present instance is in the neighborhood of 2400 R. P. M., rings 54 and 67 are acted upon by centrifugal force and tend to roll down their respective inclines 49 and 49a. The portions of the rings on the open side of the runners roll down into contact with, and are stopped by flat portions 48 and 48a. The rings are thereby maintained in spaced relationship to allow abrasive to be centrifugally discharged from the mechanism, and as seen in Figure 6, the rubber is somewhat deformed into surface contact with these surfaces by virtue of the considerable centrifugal force acting upon the 15 rings.

Under the conditions just described, the portions of rings 54 and 67 which are disposed on the closed side of the apparatus, which in this instance is the upper portion of the runners, are 20 also acted upon by centrifugal forces of equal magnitude, but as the peripheries of the driving and driven runners are more closely disposed in the upper region of the apparatus, rings 54 and 67 cannot roll down planes 49 and 49a into contact with flat portions 48 and 48a of the driving and driven runners respectively. Accordingly 25 rings 54 and 67 engage each other under considerable pressure and are slightly deformed (Figure 6), and they react against the driving and driven runners with considerable force. Centrifugal force is accordingly utilized to seal the device against the escape of abrasive on the closed side of the apparatus. Rings 54 and 67, in moving from the positions they assume on the closed 30 side of the device into the positions they assume on the open side of the device, roll down inclines 49 and 49a under the influence of centrifugal force and undergo a torsional or longitudinal deflection or twist. This action also occurs when 35 rings 54 and 67 are rolled up inclines 49 and 49a against the action of centrifugal force from the positions they assume on the open side to the positions they assume on the closed side of the 40 runners.

As these occur each cycle, or once every revolution of the runners, it is apparent that the rings must be of a material that possesses sufficient resilience to stand this action. I have found that comparatively soft rubber rings are admirably suited for this purpose, although it is to be 50 understood that if desired, other materials may be used in the device without departing from the spirit of my invention.

It should also be observed that as rings 54 and 55 67 move from their retracted or closed position into their extended or open position, they undergo a purely rolling action on planes 49 and 49a, with the result that substantially no friction is involved and substantially no heat is developed in 60 the rings and they accordingly have a long life. As a matter of fact, centrifugal force is so great that it causes portions of the rubber rings to be deflected slightly downwardly into circumferential grooves 51 with the result that they cooperate therewith to form in effect racks and pinions, to insure against slippage during operation. Accordingly, if desired, rings 54 and 67 may be 65 provided with corrugations to fit into grooves 51 and insure rolling movement thereof, as distinguished from a sliding action.

With reference to the upper portion of Figure 6, which illustrates the closed side of the runner assembly, it is observed with the machine running that rings 54 and 67, under the influence of 70 centrifugal force cooperate to define a toggle

joint having arms 135 and 136. Arm 135 applies what may be termed an "active" force to portion 49 of driving runner 33 and arm 136 applies what may be termed a "reactive" force to portions 49a of driven runner 57. These forces result in urging driven runner 57 to the right against the action of spring 127 when the machine is started and attains normal running speed, and it is this force that holds the bearing assembly with boss 109 spaced from ratchet member 116 with the 10 running clearance designated as 137 therebetween. It is apparent that should the machine be stopped, the centrifugal forces acting on rings 54 and 67 will drop to zero and spring 127 will move the driven runner to the left, thereby compressing rings 54 and 67 and taking up clearance 15 137. By reason of boss 109 engaging ratchet member 116, the rings are relieved of the full pressure of spring 127 when the machine is not in use. 20

As previously indicated, it is highly desirable that a predetermined pressure be exerted upon rings 54 and 67 in order to predetermine the proper operation of the mechanism, and to this end nut 129 is preferably adjusted on screw 111 25 at the factory, or the parts (nut 129 and screw 111) marked so as to place spring 127 under a predetermined compression. When the machine leaves the factory and has been placed in use the runners are brought up to normal operating 30 speed, latch 121 is lifted and screw 111 is turned so as to bring hair lines 118 and 119 into registry. This assures that the parts will be placed under the proper pressure and that proper operation of 35 the machine will ensue.

Assuming now that the machine is operating at normal running speed (2400 R. P. M.) and that the desired types of abrasive (metal grits, sand, etc.) are introduced into funnel 106, when the abrasives initially strike sleeve 63 they are 40 picked up from a substantially stationary condition, rotatably speaking, but as the surface of member 63 is fairly close to the axis of revolution of the driven runner, the surface which the abrasive strikes is not rotating at an excessive 45 peripheral speed, and therefore the abrasives are picked up with a minimum of wear to this part. Rotation of the various elements sets up an air current which produces a suction in the driven runner and the incoming air-stream assists feeding the abrasive to the left. As the abrasive moves to the left from sleeve 63 it is gradually accelerated, and as wall 62 is of gradually increasing diameter the abrasives are further accelerated as they move to the left. As the abrasives pass over the left hand end of wall 62 they drop into the distributor plate assembly wherein 50 they are gradually accelerated as they drop from ledge to ledge in the manner previously described. When the abrasives are finally deposited upon the closed side of the ring, which in this instance is the upper part of the apparatus, they form a substantially stationary deposit between the crotch of rings 54 and 67, as indicated in Figures 55 3 and 6. The depth of the deposit, and hence the 60 volume of abrasive discharged, will depend upon the quantity of abrasive supplied the machine. A layer of abrasive which is substantially stationary with respect to the peripheral velocity of rings 54 and 67 is accordingly deposited upon the 65 latter, and when the rings reach the open side of the machine and spread apart, the layer of abrasive is centrifugally discharged from the machine from a substantially stationary condition with 70 respect to the rings, with the result that wear of 75

the latter is minimized. The abrasive accordingly leaves the wheel substantially tangentially to the faces of the rubber rings. This condition is illustrated in Figure 2 of the drawings. If it is desired to increase or decrease the width of the abrasive blast or stream issuing from the wheel, this may be controlled to some extent by adjusting the pressure on spring 127. It is preferably adjusted however by inserting shims 91 between or withdrawing the shims from between support 88 and cover 16 in order to increase or decrease the angle 58. If it is desired to decrease the width of the abrasive blast or stream, support 88 is adjusted so as to decrease angle 58 whereas if it is desired to increase the width of the abrasive blast, angle 58 is increased.

Abrasive is therefore continuously passed through the machine, and it is observed that although the major part of the abrasive issuing therefrom has previously been deposited in the crotch of the rings, a certain amount of abrasive drops directly from tortuous passage 41 into the open discharge gap. As the runners recede from the open side position, it is apparent that as the rings contact and close the opening, and as the runners approach each other, rings 54 and 67 will contact each other and roll up inclines 49 and 49a respectively against the action of centrifugal force and the pressure set up between the rings effectively seals them against abrasive leakage.

It is therefore observed that the rings are continually rolled around circumferentially in the grooves in the respective runners, and in effect undergo a tilt every revolution, and this tends to cause an air current to travel circularly in the grooves in a direction opposite to the direction of rotation of the runners. This air current might interfere with proper opening and closing movements of the rings if grooves 44 and 56 were entirely closed, and I have therefore provided apertures 53 and 53a at spaced points in the driving and driven runners respectively in order to establish atmospheric communication with the grooves and allow air to freely enter and be exhausted therefrom in response to the pulsating action of the rings therein. This prevents a vacuum from being established behind the rings and also provides effective ventilating currents. A rod may also be inserted through apertures 53 for removing and replacing rings 54 and 67.

In view of the fact that the terminus of tortuous passage 41 is disposed opposite the meeting faces of rings 54 and 67, most of the abrasive is deposited upon the latter. However, some abrasive may get behind rings 54 and 67, and this abrasive works downwardly into circumferential grooves 51 and it is centrifugally drained from these grooves by intersecting drain holes 52 and 52a associated therewith. It is therefore seen that rings 54 and 67 are assured of a clean surface upon which to roll, with the result that their rolling action does not abrade them in the least.

The centrifugal fan effect produced by the skin friction of the various rotating parts has previously been described as useful in feeding the abrasive into the device. These air currents are also very beneficial from the standpoint of ventilation, as they flow over all the parts and maintain the temperature at a safe value. The heated air is adapted to be exhausted at the open side of the apparatus and also through a plurality of exhaust ports 64 provided in the driven runner. If desired similar ports may be provided in the driving runner.

This machine may be used in various relation-

ships, for instance, it may be mounted within a cabinet to clean articles tumbled or passed therethrough or it may be of a portable character and moved from place to place to perform any desired cleaning or blasting operations. In order to prevent articles from coming into contact with the rotating head and to also prevent extraneous abrasives from being discharged at random into the air, I preferably provide the apparatus with a guard which comprises segmental shield members 141 and 142 which are secured to the lower face of base A in any suitable manner. Shield 142 is provided with a partition 143 and a baffle plate 144 having a perforation 145 in its lower region. As abrasive gravitates through an opening 146 formed in base A it is guided by baffle 144 to perforations 145. As the abrasive finds its way through perforations 145 it drops into shield 142 and gravitates outwardly of the apparatus by way of an opening 147 in partition 143. Abrasive thrown from any of the rotating parts which might ricochet upwardly through passage 147 in partition 143 and then into the bearings is arrested by the unperforated portion of baffle 144.

After the machine has been in use for some time rings 54 and 67 will wear to some extent, but spring 127, acting upon the driven runner in the manner previously described, causes the driven runner to move toward the driving runner and compensate for this wear. When the rings have become worn to a greater extent, boss 109 will move into contact with ratchet member 116 and at this time is preferable to restore the original spring pressure. This is preferably effected by lifting latch 121, and turning screw 111 inwardly by means of squared portion 111 to bring hair lines 118 and 119 into alignment. Operating screw 111 in this manner causes the entire assembly to be pulled to the left because this action threads screw 111 into or toward support 88. When the hair lines have been brought into registry, latch 121 is dropped into place. This operation is effected while the machine is operating and it accurately restores the original spring pressure with which the machine was originally put into operation, for the reason that it restores the original relationship of spring 127 and sleeve 17 and thereby puts rings 54 and 67 under the original pressure.

As previously described, nut 129 is turned up to a predetermined point on screw 111 at the factory and that thereafter all adjustments to compensate for wear are effected by screw 111. If desired, this procedure may be omitted and the machine calibrated by adjusting nut 129 after the machine is started. This operation is effected in the following manner. The parts are assembled and nut 129 is taken up to a certain extent to place some pressure upon spring 127. The machine is then started and abrasive is supplied thereto. Screw 111 is then rotated to bring hair lines 118 and 119 into alignment and latch 121 is dropped in place to lock screw 111 against turning movement. The character of the blast stream issuing from the machine is then carefully observed and nut 129 is turned in the proper direction to bring about the proper blast stream. While this adjustment is being effected, the changes in the spring pressure may be sufficient to cause boss 109 to move to the left or right and bring hair lines 118 and 119 out of registry, and if this occurs, the screw 111 should be adjusted to bring them into registry before the final adjustment is given nut 129. When the blast stream assumes a proper configuration, nut 129

is then locked in place in any suitable manner (not shown) and the machine is operated as previously described. Thereafter, upon wear of rings 54 and 67, screw 111 is manipulated in the manner previously described in order to compensate for wear of the rubber rings, and nut 129 is left undisturbed as it has been previously calibrated to give the desired spring pressure with hair lines 118 and 119 in registry.

10 When rings 54 and 67 have become so worn as to be unfit for further service, the machine is disassembled and the rings replaced in the following manner. Nut 129 is backed off to relieve the driven runner of pressure and the whole assembly is moved to the right (Figure 3) to bring hub portion 59 of the driven runner out of engagement with the opening in distributor plate 36. Nut 21 is then loosened and stud 26 is swung outwardly about its pivot to bring it clear of ears 28 of cover 16. Handle 20 is then grasped and the whole assembly lifted upwardly about pin 23 as an axis. It is apparent that with cover 16 raised in this manner, both the driving and the driven runners are exposed throughout 360° of their area 25 and the rings as well as distributor plates 35 and 36 may be replaced and any other part inspected.

With the cover 16 raised in this manner, a screw driver or the like is inserted in the grooves behind rings 54 and 67 and the latter removed 30 therefrom. Two new rings are then inserted in the grooves and although the edges of the groove 44a are smaller than the diameter of the rings, the latter are soft and pliable and may be readily worked into place by inserting a portion thereof 35 in the groove and then working progressively around the ring to get the entire ring into position in the groove. After the rings have been replaced in the manner just described, cover 16 is lowered into place, the driven runner is then 40 shoved forwardly to bring the rings into contact with each other at the closed side of the apparatus and nut 129 is screwed in place on screw 111. The machine then may be placed in operation and adjusted and calibrated in the manner 45 previously set forth.

Although I have illustrated a device employing rings that are axially movable with respect to the driving and driven runners, and I prefer to employ this arrangement, as it possesses the advantages pointed out in detail, it is to be understood that if desired they may be omitted and one or both of the runners provided with a soft or yielding edge so as to seal the device against abrasive discharge on the closed side of the device, and the appended claims are intended to embrace my apparatus when it assumes this form. Moreover, as my invention in its broadest aspects comprises a rotatable mechanism adapted to receive abrasive and having means for discharging the abrasive from the wheel as it progressively reaches a predetermined point, the rubber rings illustrated, which constitute an infinite number of valves, may be substituted by a plurality of valves of any other description, such as mechanical valves having a mechanism for tripping them each revolution of the runners, without departing from the spirit of my invention.

It is to be particularly observed that in the present instance the axes of the driving and 70 driven runners intersect at a point that is substantially radially opposite the contacting portions of the two rubber rings, in order that the runners will run true. In other words, if the runners were eccentrically mounted, the rubber 75 rings on the closed side of the assembly would

undergo a constant radial movement in and out in their respective grooves by reason of the eccentric character of the two runners. However, a slight rolling or weaving action of this character is not harmful and therefore it is only necessary to secure approximate alignment of the driving and driven runners.

With reference to Figure 2, it is observed that cap screws 89 pass through elongated slots 90 in supports 88 with the result that cap screws 89 10 may be loosened and the entire support rocked slightly clockwise or anti-clockwise to direct the abrasive discharge at different angles. If desired, the entire machine may be mounted in a cradle or the like for rocking movement about 15 the axis of shaft 14 so that the abrasive blast may be directed at any desired angle. Moreover, the machine may be mounted for rotation in a cradle or the like about the axis of shaft 14 and be driven by a slow speed gear arrangement or 20 the like for causing the blast to travel through 360° for cleaning the interior of cylindrical bodies or the like.

With reference now to Figure 7 of the drawings, I have shown a modified form of ring assembly, associated with the runner assembly shown in Figures 1 to 6, inclusive. With continued reference to this figure, distributor plate 35 is provided with an outwardly extending flange 151. Driven runner 57 is provided with a similar 30 flange 152. Rubber rings 54a and 61a, which are disposed in grooves 44 and 66, are provided with circumferential lips or flanges 153 and 154 respectively, which cooperate with flanges 151 and 152.

This form of my invention functions in precisely the same manner as that just described, as rings 54a and 61a are free to roll up and down the inclined portions 49 and 49a of the driving and driven runners, but in this instance it is observed that as lips 153 and 154 contact flanges 151 and 152 when the rings roll toward each other, the rings are definitely stopped in predetermined positions, and it is not necessary to give inclined portions 48 and 48a of the runners 45 as steep a pitch, because they do not constitute the sole limiting means for the rings, as do the corresponding portions in the first form of my invention.

When it is desired to replace the rings, the operation is carried out in exactly the same manner as that described in connection with the first form of my invention and when the new rings are inserted in the grooves, the lips 153 and 154 are inserted first and each ring is pushed into 55 place and progressively inserted throughout the circular extent of the runner.

With reference now to Figures 8 and 9 of the drawings, I have illustrated a further modified form of ring assembly, and in this form of the invention the distributor plates are also of a slightly modified construction.

With continued reference to these figures, distributor plate 35a is connected to distributor plate 36a in a manner similar to that shown in the device of Figures 1 to 6, and the outer edge of plate 35a is provided with a plurality of fins 161 which are staggered with respect to a plurality of similar fins 162 formed on distributor plate 36a. Distributor plate 35a is also provided with a plurality of radially extending passages 163 and plate 36a is provided with a plurality of similar passages 164. The passages and fins just described serve to distribute the abrasive over a wider area than the distributor plate arrangement used in 75

- the first form of my invention for the purpose of spreading it over the wide ring arrangement used in this device and which will now be described.
- Driving runner 33a is provided with an annular groove 44a which is provided with a substantially cylindrical outer surface 166, with the result that ring 54a does not tend to undergo axial movement in response to centrifugal force.
- Groove 66a of driven runner 57a and which contains ring 67a is constructed in a similar manner to have a cylindrical outer wall 167. However, if desired the outer walls of groove 44a and 66a may be inclined so as to enable rings 54a and 67a to respond to centrifugal force and augment their ring compressing action.

Disposed between rings 54a and 67a is the preferably integrally formed rubber ring 168 of cylindrical shape and it is held therein by the outer wall of grooves 44a and 66a and at its inner edges is guided by lips 170 and 171 formed on the driving and driven runners respectively. Ring 168 is provided with a plurality of circumferentially spaced slits 172 having beveled upper edges 173. The central portion of ring 168 is preferably provided with a plurality of reinforcing members 175, which may be of cord or wire, and which are integrally molded in the rubber. Reinforcing members 175 function to prevent the central portion of the rubber ring from bellying out in response to centrifugal force.

The operation of this device is somewhat similar to the forms of my invention previously described and assuming that when the wheel is operating at normal running speed, screw 111 is adjusted so that the upper side of the wheel, by reason of the axial difference of the driving and driven runners, will be closed. Closing slits 172 in this device is effected by driving and driven runners acting through rings 54a and 67a which deform the cylindrical ring 168 and force the walls of the slits into tight sealing engagement.

When the machine is adjusted to give proper tension the operation is as follows. Abrasive trickles outwardly through tortuous passage 41 and then passes between blades 161 and 162 into passages 163 and 164 of the distributor plates where it is deposited upon the tapered beveled faces 173 of the slits 172. As the runner assembly rotates into open or discharging position, slits 172 open up, through the inherent resilience of the rubber, and allow the deposited layer of abrasive to be centrifugally discharged therethrough. When elements 168 wear in response to normal use, the pressure on the driven runner is increased by adjusting screw 111 as previously described in connection with the first forms of my invention. When it is desired to replace member 168 the machine is disassembled and the parts replaced in the manner as that previously described.

Although I have illustrated and prefer to employ a pair of rubber rings 54a and 67a to compress cylindrical ring 168 and close the openings therein, they may be omitted if desired and ring 168 be allowed to extend the full width of the device and into the groove in the respective runners. Moreover rings 54a and 67a may be augmented or substituted by a resilient means of any other desired character, for instance a circular leaf spring or the like.

With reference now to Figure 10 of the drawings, I have illustrated a further modified form of abrading apparatus which is somewhat similar to that just described. In this form of the in-

vention driving and driven runners 33b and 57b are provided with grooves 44b and 66b which are adapted to receive the outermost pair of three separate rings 181 of preferably identical construction. Each ring 181 is made up of a rubber body portion 182 and a steel reinforcing ring 183 which is T-shaped in cross-section and which controls the action of the rubber under the influence of centrifugal force. Each ring 181 is provided with a beveled portion 184 so as to define V-shaped abrasive receiving grooves when they are disposed on the closed side of the apparatus.

Distributor plates 35b and 36b are secured to driving runner 33b in a manner similar to that disclosed in the previous forms of my invention, but the outer periphery of plate 35b is provided with a plurality of teeth or blade members 185. The outer peripheries of teeth 185 are turned to provide substantially true cylindrical surfaces 186 upon which central ring member 181 is mounted. Distributor plate 36b is provided with a plurality of teeth 187 which interengage with teeth 185 of plate 35b. As seen in Figure 10 teeth 185 and 187 provide a plurality of passages through which abrasives may pass from tortuous passage 41 to the spaces between the three rings.

The operation of this form of my invention is somewhat similar to that previously described. When the runners have been brought up to speed abrasive is fed to the device and as it passes through the spaces between the interengaging teeth it will be guided into the V-shaped receptacles defined by the inner edges of rings 181, upon which it is deposited.

Spring 127 is placed under the requisite degree of compression to insure that the sealing engagement of rings 181 will prevent abrasive leakage from the portions of the ring on the closed side of the apparatus. When the runners attain open side position, the pressure is relieved from them, and spaces will develop therebetween, as illustrated in the lower part of Figure 10, and the abrasive previously deposited upon them is then centrifugally discharged from the apparatus. It is observed that the steel reinforcing members 183 are so related to the ring that they are not subjected to the action of the abrasive, with the result that when the rings are removed and replaced, the old rings may be remolded and used over again by employing the original reinforcing elements as the foundation for new rings.

With reference now to Figure 11 of the drawings, driving runner 33c and driven runner 57c are mounted for rotation in precisely the same manner as the driving and driven runners of the previously described apparatus. In this form of the invention the distributor plates are substituted by a funnel shaped member 191, which is secured to the driven runner in any suitable manner as for instance by means of cap screws 192. Member 191 operates as an abrasive distributing and accelerating member and flares outwardly and terminates adjacent an annular groove 193 formed in a removable cylindrical wear-ring 194. Member 194 is provided with a flaring apron portion 195, which is provided with a plurality of apertures 196 through which the abrasive is adapted to be fed to the rings.

The ring assemblies shown and described in connection with the modifications of the invention illustrated in Figures 8, 9 and 10, may be used in this device, but I preferably employ a plurality of rubber rings 198, which have cords 199 molded therein for the purpose of reinforce-

ing them against distortion in response to centrifugal force. Rings 198 seat in grooves 44c and 66c provided in the driving and driven runners 33c and 51c respectively. The outer rings 5 198 are also guided by means of rings 201 and 202 which are secured to the driving and driven runners respectively. The driven runner is also provided with ventilating holes 65, and apron 195 has ring centering ribs 200.

10 Basically, the operation of this device is similar to that of those previously described, and when the machine has been brought up to speed and spring 127 has been placed under sufficient compression so as to force rings 198 into proper sealing 15 engagement on the closed side of the device, the abrasive is admitted to the machine. The abrasive is gradually accelerated by walls 62c of the driven runner and it spreads outwardly over the inner surface of member 191 where it 20 receives a further acceleration and is spread out so that it is uniformly deposited in groove 193 of member 194. As indicated in Figure 11, groove 193 always contains a substantial quantity of abrasive, with the result that the bottom of the 25 groove is never subjected to the direct abrading action of the abrasive leaving member 191. The abrasive overflows from groove 193 onto apron 195, where it is evenly distributed and finds its way through openings 196 to the inner sides of the 30 rings. A part of the abrasive travels past openings 196 and is deposited upon the right-hand pair of rings of the device. When the rings attain the open side of the device pressure is relieved from them and they spread apart to 35 allow the layers of abrasive deposited thereon to be centrifugally discharged from the device. As the adjusting and part replacing operations of the construction are identical to those of the previously described mechanisms they will not be further set forth.

40 In Figure 12 of the drawings I have illustrated a modified form of abrasive ring assembly which may be employed in all of the illustrated constructions except that shown in Figure 1, and it consists of a metallic ring 204 which is substantially H-shaped in cross section. Frictionally disposed or vulcanized in place in each of the grooves formed in the opposite sides of each ring 204 is a rubber ring 205 which is adapted to 45 frictionally cooperate with the rubber ring of an adjacent ring assembly. These rings function substantially in the same manner as those previously described as the rubber elements thereof undergo compression when the rings are compressed on the closed side of the apparatus and, 50 when they are on the closed side of the device, they define a plurality of annular depressions into which the abrasive is deposited.

55 At this point a brief comparison of the characters of the abrasive streams issuing from the respective machines illustrated will be set forth. With reference to the machines shown in Figures 1 to 7 inclusive, the opening on the open side of the machine assumes the form of a slit having tapered ends. The abrasive discharged from the 60 leading edge of the slit has, up to the time of discharge, been resting in a substantially stationary condition upon the rings, with the result that it is discharged in a substantially tangential direction but in restricted volume by reason of the restricted area of this part of the slit. The abrasive issuing from the central and trailing 65 portions of the opening takes a different direction, as seen in Figure 2, for the reason that a 70 part of this abrasive is thrown directly from the

distributor plate assembly through the opening and as this abrasive possesses both radial and tangential components, it will take a direction which is inclined to a tangent from the rings. The abrasive is discharged from the machines 5 shown in the other figures in very much the same manner, and with reference to the device shown in Figures 8 and 9, wherein a single slotted ring is employed, it is apparent that as the slits pass through the opening cycle, they will initially open 10 to a slight extent, so as to discharge a part of the abrasive deposit thereon in a tangential direction, and will then open to their fullest extent to discharge the remainder of the abrasive deposit and also abrasive thrown directly from the distributor plate assembly. The slits will then close 15 and cause a fresh abrasive deposit to be built up thereupon for discharge during the next cycle of operation.

20 It is therefore apparent that the abrasive stream discharged from all of my machines is substantially uniform throughout its width, as distinguished from the non-uniform discharge of prior paddle wheel machines.

25 In connection with all of the forms of my invention disclosed herein, it is to be observed that although I have illustrated and preferred to journal the driven runner in bearings, so as to maintain it in a definite position, if desired, the bearings for the driven runner may be omitted and 30 the latter carried directly by the driving runner without departing from the spirit of my invention. For instance, with reference to Figure 1, and Figure 3, driving studs may be secured to driving runner 33 and extend through apertures 35 in the rear wall of driven runner 57 to provide a driving connection, and compression springs may encircle studs and bear against the rear face of the driven runner and against the heads of nuts threaded on the studs. These spring assemblies 40 will provide a driving connection between the driving and driven runners and at the same time will urge them toward each other so as to place the rubber elements under compression on the closed side of the machine. The driven runner may be tilted in this device, so as to provide a discharge point, in any suitable manner, as for instance by providing the driven runner with a raceway and associating therewith a stationary supported, axially adjustable roller to urge one 45 side of the driven runner to the left a slight distance to predetermine the discharge point.

50 In the device just described, rollers may be mounted for axial movement, in order to provide for adjustment of the size of the discharge opening, and the spring pressure may be adjusted by tightening or loosening the nuts on the studs. If desired, however, the arrangement of the parts of this device may be reversed, and the springs 55 be employed to urge the runners away from each other and the roller may be located at the closed side, and operate under the action of an adjustable spring to force the driven runner toward the driving runner. Any suitable means may be employed to prevent the driving and driven runners 60 from moving apart too greatly at the open side of the machine; for instance, shoulders may be formed on the studs.

65 Although I have illustrated an apparatus 70 wherein the abrasive is admitted thereto by way of the driven runner, it is to be understood that it may be admitted in any other suitable manner, as for instance by way of the driving runner 75 and the appended claims are intended to embrace

my invention when it assumes this form. Moreover, I have shown a device wherein the shims 91 may be removed or inserted between the parts so as to vary the axial difference between the driving and driven runners, but it is to be understood that if desired any other suitable form of mechanism for selectively adjusting the position of the driven runner with respect to the driving runner may be employed without departing from the spirit of my invention. For instance, an eccentric sleeve may be employed to support the sleeve member 77, and be so designed that rocking movements of the eccentric sleeve will cause the angle 58 to increase or decrease to any predetermined value. Moreover such eccentric sleeve may be rocked by a power means and synchronized with the operation of the apparatus with which the machine is used so as to produce a varying abrading action, i. e. a stream of fluctuating width, or any other action, in any suitable manner. It is also to be understood that the eccentric device just mentioned may be employed to bring driving and driven runners into alignment with the result that when they are forced together they will close the abrasive chamber defined by the head throughout 360° of their circumference to positively shut off the abrasive stream. On the other hand, should the runners be separated a slight amount while their axes are in alignment the machine will discharge the abrasive through 360° of their circumferences which may be used to advantage in certain abrading operations.

Although I have illustrated in Figures 10, 11 and 12 of the drawings, a device using a plurality of rings, which gives a comparatively wide blast stream, it is to be understood that if desired for the machines to give a narrow stream, one or all of the intermediate rings may be omitted thereby give a blast having a narrower abrasive stream. Moreover, the two rings which are associated with the driving and driven runners respectively in such device may be of hollow construction and inflated to a predetermined pressure to enhance the sealing action thereof when they are pressed together, and it is to be understood that the appended claims are intended to embrace my invention when it is embodied in this form.

I have found as a result of experiment that the pressure which must be exerted by spring 127 upon the driven runner when the machine is operating lies in the neighborhood of 800 pounds for the machine illustrated in Figures 1 to 7 of the drawings, and that for the machine illustrated in Figures 8 to 12 inclusive, the pressure lies in the neighborhood of 2000 pounds. It is to be understood, however, that these pressures and also the speed at which the machine must be driven will depend upon the size of the wheel. For instance, if a larger wheel is used, the speed may be reduced, because of the greater radius from which the abrasive is thrown, and the spring pressure will probably have to be increased.

Although I have illustrated, and prefer to employ a spring assembly for applying pressure to the driven runner, it is to be understood that if desired a hydraulically or pneumatically operated piston and cylinder assembly may be employed to urge the parts together, utilizing a source of hydraulic or air pressure having a constant value in order that the parts will be urged together under a predetermined force at all times.

With this form of the invention it is apparent that

wear of the rubber element will be automatically compensated for by reason of the constant pressure applied thereto, and that the driven runner will accordingly move toward the driving runner as wear of the rubber elements takes place. This 5 obviates the necessity for adjusting screws or nuts. If desired the air or fluid pump may be driven synchronously with or controlled synchronously by the operation of driving shaft 14 in order to automatically relieve the rubber rings 10 of pressure when the machine is stopped. If desired a fluctuating pressure source may be used and a pressure regulator interposed between the source and the cylinder. As most pressure regulators are adjustable, it is apparent that with this 15 assembly the pressure with which the rubber ring is gripped between the runners may be accurately adjusted. A valve may also be provided to instantaneously relieve the runners of pressure.

In Figure 13 I have illustrated one form of 20 mechanism that may be used in lieu of the spring organization shown in Figure 4. In this form of my invention, boss 109a is provided with a flat rear face, to which is secured, by means of cap screws 209, a piston rod sealing assembly 210 and 25 a cylinder head 211. Secured to head 211 by bolt and nut assemblies, and having a gasket clamped therebetween, is a cylinder 212 having an apertured end 213.

Screw 111a, which is of slightly modified form, 30 extends loosely through boss 109 and into cylinder 212. Secured to screw 111a, by means of a nut 214, is a piston assembly 215. Screw 111a accordingly functions as a piston rod, but as it is carried by stationary support 88 its position is 35 fixed, while the cylinder, which is connected to sleeve 77, is adapted to undergo movement in response to fluid pressure.

Communicating with cylinder 212, by means of a fitting 217, is a pipe 218, which is connected to the low pressure side of a pressure regulator 219. Pressure regulator 219 may be of any desired conventional form, and is preferably equipped with an adjusting screw 221, which may be manipulated to increase or decrease the regulator spring 45 pressure to thereby increase or decrease the air pressure delivered to pipe 218, in well known manner. Air may be supplied to the high pressure side of the regulator from a compressed-air source, whose minimum pressure is in excess of 50 the low pressure side, by any suitable means, such as a flexible hose 222, and a valve 223 is preferably inserted in line 218 for controlling the air supply to the cylinder. Valve 223 is so designed that when handle 224 thereof is disposed in its full line position, the cylinder will be in fluid communication with the regulator, and when disposed in its dotted line position the cylinder 55 will be in fluid communication with the atmosphere.

The machine may be placed in operation as described in connection with the first forms of my invention, and control valve handle 224 is preferably rocked into its full line position simultaneously with, or prior to starting the runner, so that the driving and driven runners will be disposed in driving engagement when the machine is brought up to speed. If desired this coordination of operation may be attained by connecting valve handle 224 to the starting mechanism of 70 the prime mover, or mechanism responsive to the speed of the driving runner may be used to control the valve.

When air pressure is admitted to cylinder 212, it is apparent that it will react against piston 215 75

and act against cylinder head 211 to cause the latter to move to the left and bring the driven runner into frictional engagement with the driving runner. If desired, particularly when this assembly is used with the machine shown in Figure 1, a nut 225 may be adjustably threaded onto screw 111a to limit the movement of boss 109a and the related parts under the influence of air pressure, so that when the runners are stopped, or are being started, the air pressure will not compress the rings and bring the runners into actual contact. If, however, operation of the valve is coordinated with operation of the starting mechanism, as above described, nut 225 may be omitted and a restriction placed in pipe 118, so as to retard air flow into cylinder 212, to thereby delay attainment of full pressure until the runners have been brought up to normal running speed.

With the machine running, and with the air control valve open, the parts assume the position shown in Figure 13, and it is apparent that the runners are urged together under a predetermined pressure. When the machine is initially placed in service, screw 221 is adjusted to establish proper pressure conditions, and this adjustment is preferably made with the machine in operation, as the blast stream can then be observed and screw 221 adjusted accordingly. After this adjustment has been made the setting thereafter need not be disturbed, unless other adjustments are made that would require an increase or decrease in pressure (for instance, installing different type rubber rings, changing angle 58, etc.).

It is therefore seen that the pneumatic cylinder exerts a constant pressure upon the driven runner at all times, with the result that although the rubber rings will wear in service, and the driven runner will move to the left under the influence of the cylinder assembly, and compensate for the wear, the pressure will nevertheless remain constant, and the apparatus is therefore self-adjusting for wear.

The piston and cylinder area and the pressure regulator delivery pressure are preferably designed so that a pressure of approximately eight hundred pounds is exerted when the pneumatic control is used in the first form of my invention, and a pressure of approximately two thousand pounds is exerted when it is used in the other forms of my invention. If desired, however, the pressure regulator may be omitted if a source of substantially constant air pressure is available.

Although I have illustrated and prefer to employ a pneumatically operated device, because air is elastic and urges the runners together with a yielding pressure, it is to be understood that the cylinder assembly may be energized by oil or other liquids or gases, without departing from the spirit of my invention, and the term "fluid", as employed in the appended claims, is therefore intended to embrace these energizing media.

As previously explained, the parts are illustrated in Figure 13 as they appear when the machine is operating at normal speed, and it is seen that a considerable clearance exists between cylinder head 211 and the piston assembly. This clearance is provided so that when the machine is stopped with the air pressure cut off, and it is desired to lift the cover and replace the rings, the driven runner assembly may be readily slid rearwardly to clear the other parts and the cover lifted. In this connection, I preferably mount

the pressure regulator upon boss 109a or the cover, so that it will lift upwardly as a unit with the cover. Of course, if the regulator is mounted on the cover, pipe 118 will be of a flexible character, so as to permit the driven assembly to move toward and away therefrom.

In most installations where apparatus of the character disclosed herein are used, compressed air is usually available and supply pipe 222 may accordingly be connected thereto. However, if a compressed air source is not available, pipe 222 may be connected to a suitable pump, preferably driven by driving shaft or by the motor thereof so that pressure will automatically build up in cylinder 212 as the machine is started. Such pump would preferably be similar in design to the simple cam and lever type pumps now in wide use in automobile fuel pumping systems, which automatically cease pumping when fluid flow is cut off. By using a pump of this character, a minimum of power would be required as it would cease operating as soon as sufficient pressure had been built up in cylinder 212 to close the regulator valve and cut off communication between the pump and cylinders.

In the forms of invention illustrated in Figures 1 to 7 inclusive and 10, 11 and 12, frictional engagement of the rubber rings is operable to seal the head, defined by the runners against abrasive discharge on the closed side of the machine and is also effective to effect a driving connection between the runners. In the device shown in Figures 8 and 9, a single slotted ring is used and although frictional engagement of the walls of the slits on the closed side of the device seal the head against abrasive discharge, such frictional engagement plays only a minor part in establishing a driving connection between the runners, because of the bodies of rubber disposed directly therebetween. It is therefore apparent in all of the forms of my invention the head is sealed against abrasive discharge on the closed side of the machine by frictional engagement of the rubber, and the term "frictional engagement" employed in the appended claims is therefore intended to cover this feature irrespective of whether the driving and driven runners are frictionally or mechanically connected together for synchronous rotation or are each driven by an individual prime mover.

I have shown the driven runner as being journaled independently of the driving runner, and I prefer to employ this arrangement, but it is to be understood that if desired one end of the driven runner may be journaled upon the driving runner by any suitable means as for instance by means of a spherical or self-aligning dust-proof bearing or a universal joint, the latter preferably being of the non-accelerating type.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. An abrasive propelling device comprising a pair of members mounted for independent rotation, said members being disposed with their

axes inclined at an obtuse angle to each other, means disposed between said members and cooperating therewith to seal said members against abrasive flow therebetween throughout a portion 5 of each revolution, and to allow abrasive to flow therebetween throughout another portion of each revolution, and means for feeding abrasive between said members adjacent the axes thereof.

2. The device described in claim 1, wherein said 10 means comprises at least one annular flexible element frictionally gripped between said members.

3. An abrasive propelling device comprising a rotatable member having substantially circularly 15 disposed, axially facing sealing faces, a second member adapted to rotate synchronously with said first member and also having substantially circularly disposed, axially facing sealing faces, and means for causing said members to rotate 20 with a portion of their sealing faces in engagement, and means for feeding abrasive between said members.

4. The device described in claim 3, wherein said 25 means comprises means for causing one of said members to tilt with respect to the other member.

5. The device described in claim 3, wherein the sealing faces of said first and second members are provided in an element which is frictionally 30 gripped between said members.

6. An abrasive propelling apparatus comprising at least two members mounted for synchronous rotation and having at least one resilient element disposed therebetween, said members being disposed with their axes inclined at an angle of somewhat less than 180° to each other, said members and element defining an abrasive chamber, means for introducing abrasive into said chamber, and means for causing said resilient element to 35 seal said members against abrasive egress during one portion of each revolution of said members, and to automatically provide at least one opening and allow abrasive to be discharged from said chamber during another portion of each revolution of said members.

7. The device described in claim 6, together with resilient means for urging said members toward each other and into engagement with said element.

8. An abrasive propelling device comprising a 50 pair of members mounted for synchronous rotation and adapted to define an abrasive chamber, means for feeding abrasive between said members, at least one of said members having a flexible element carried thereby for controlling the discharge of abrasive from said members, means for causing said flexible element to move toward, and apply forces to said other member in response to centrifugal force when said members are 55 rotated, and means for urging said members toward each other against the action of the forces developed in said flexible element, said flexible element operating to seal said members against abrasive flow therebetween throughout a portion 60 of each revolution, and to allow abrasive to flow therebetween throughout another portion of each revolution, and means for feeding abrasive between said members.

9. The device described in claim 8, wherein 65 said means is resilient and is selectively operable to apply forces of varying magnitude to said members.

10. For use in an abrading apparatus having 70 at least one rotatable runner from the periphery 75 of which abrasive is centrifugally discharged, a

pair of abrasive distributing members adapted for synchronous rotation with said runner and operable to feed abrasive from a region adjacent the axis of said runner to the periphery thereof, said distributing members being of generally circular shape and having their facing surfaces so formed as to define a tortuous passage. 5

11. An abrasive propelling apparatus comprising at least two members mounted for synchronous rotation and having at least one resilient element disposed therebetween, said members and element defining an abrasive chamber, means for introducing abrasive into said chamber, and means for causing said resilient element to seal said chamber against abrasive egress during one portion of each revolution of said members, and to automatically provide at least one opening and allow abrasive to be discharged from said chamber during another portion of each revolution of said members, and means, providing a resilient air cushion, for urging said members toward each other. 10 15 20

12. The apparatus described in claim 11, wherein said members are mounted for relative axial movement, and said air cushion is operable to exert a force of constant magnitude upon said members, irrespective of their relative axial positions. 25

13. An abrasive propelling device comprising a pair of members mounted for synchronous rotation and adapted to define an abrasive chamber, a resilient deformable element frictionally gripped between said members and having a plurality of openings therein, and means for feeding abrasive to said chamber, said members being 30 mounted for rotation about non-parallel axes, to thereby cause one portion of said element to be gripped and another portion of said element to be substantially uncompressed, to thereby cause the openings in said portions to be respectively 35 closed and open for controlling discharge of abrasive from said chamber. 40 45

14. An abrasive propelling device comprising a pair of disc-like members mounted for synchronous rotation closely adjacent each other about non-parallel axes, each of said members having a groove in its periphery, the walls of each of said grooves inclining outwardly and toward the other member, a resilient element disposed in each of said grooves and cooperating 50 with said members to define an abrasive chamber, means for feeding abrasive to said chamber, said elements being responsive to centrifugal force to roll upon said inclined walls and to engage each other and seal one side of said chamber. 55

15. The abrasive propelling device described in claim 14, wherein each of said grooves is provided with a second inclined wall for limiting movement of said elements toward each other under the influence of centrifugal force. 60

16. An abrasive propelling device comprising at least two members mounted for synchronous rotation closely adjacent each other about non-parallel axes, said members cooperating to define an abrasive receiving chamber, means for feeding abrasive to said chamber, and resilient means disposed between said members and operable to maintain one side of said chamber closed at all times and another side of said chamber open at all times, and means for gradually accelerating 70 the abrasive fed to said chamber up to the peripheral speed of said resilient means as the abrasive moves outwardly in response to centrifugal force. 65 75

17. In an abrasive propelling device, a hollow

structure rotatable at high speed, said structure providing a plurality of annular abrasive supporting surfaces disposed circularly around said structure and said surfaces facing inwardly toward the axis of rotation of said structure, means for feeding abrasive to the interior of said structure and for depositing it upon said surfaces, and abrasive controlling means for causing each of said surfaces to retain abrasive thereon during a portion of each revolution thereof, and for causing the abrasive accumulated thereon to be discharged therefrom during another portion of each revolution.

18. An abrasive propelling device comprising a rotatable member, means for introducing abrasive into said member, and means cooperating with said member for preventing said abrasive from escaping from said member while the latter is rotating through a predetermined angular part of each revolution, said member being operable to propel said abrasive at abrading velocities when said member is rotated through another predetermined part of each revolution, said last named means comprising a second member mounted for rotation about an axis that is inclined with respect to the axis of the first-named member.

19. In an abrasive propelling device, a hollow structure rotatable at high speed, said structure providing abrasive supporting surfaces disposed circularly around said structure and said surfaces facing toward the axis of rotation of said structure, means for feeding abrasive to the interior of said structure and for depositing it upon said

surfaces, and abrasive controlling means for causing each of said surfaces to retain abrasive thereon during a portion of each revolution thereof, and for causing the abrasive accumulated thereon to be discharged therefrom during another portion of each revolution, said abrasive supporting surfaces constituting a continuous annular wall, and said abrasive controlling means comprising a second hollow structure mounted for rotation about an axis which is inclined with respect to the axis of said first hollow structure and co-operative with said wall to retain the abrasive thereon during a part of each revolution.

20. In an abrasive propelling device, a hollow structure rotatable at high speed, said structure providing abrasive supporting surfaces disposed circularly around said structure and said surfaces facing toward the axis of rotation of said structure, means for feeding abrasive to the interior of said structure and for depositing it upon said surfaces, and abrasive controlling means for causing each of said surfaces to retain abrasive thereon during a portion of each revolution thereof, and for causing the abrasive accumulated thereon to be discharged therefrom during another portion of each revolution, said abrasive control means comprising a second hollow structure mounted for rotation about an axis which is inclined with respect to the axis of rotation of said first hollow structure, said second hollow structure having an axially extending passage terminating in an outwardly flaring surface for accelerating the abrasive.

WALTER L. KEEFER.
